Primary Examiner — Manpreet S Matharu*Assistant Examiner* — Suzanne E Tisdell(74) *Attorney, Agent, or Firm* — Buchanan, Ingersoll & Rooney PC(57) **CLAIM**

The ornamental design for a laser emitter/receiver, as shown and described.

DESCRIPTION

FIG. 1 is a perspective view of a laser emitter/receiver showing my new design;

FIG. 2 is a front view thereof;

FIG. 3 is a back view thereof;

FIG. 4 is a top view thereof;

FIG. 5 is a bottom view thereof;

FIG. 6 is a right view thereof; and,

FIG. 7 is a left view thereof.

1 Claim, 4 Drawing Sheets(56)
